(57) **CLAIM**

The ornamental design for a lens for a light-emitting diode bulb, as shown and described.

DESCRIPTION

FIG. 1 is a top perspective view of a lens for a light-emitting diode bulb of the present design;

FIG. 2 is a bottom perspective view thereof;

FIG. 3 is a front elevational view thereof;

FIG. 4 is a top plan view thereof;

FIG. 5 is a bottom plan view thereof;

FIG. 6 is a sectional view thereof taken along line 6—6 of FIG. 3;

FIG. 7 is a sectional reference view, indicating that a light-emitting diode is attached to the lens for light-emitting diode bulb; and,

FIG. 8 is an exploded sectional reference view of the lens for light-emitting diode bulb shown in FIG. 7.

The broken lines shown in the drawings are included for the purpose of illustrating environmental structure and form no part of the claimed design.
